UNITED STATES PATENT OFFICE

WALTER T. GOLLWITZER, OF CHICAGO, ILLINOIS, ASSIGNOR TO ADDRESSOGRAPH COMPANY, OF WILMINGTON, DELAWARE, A CORPORATION OF DELAWARE

PRINTING MACHINE

Original application filed October 26, 1927, Serial No. 228,729. Divided and this application filed May 2, 1929. Serial No. 359,775.

This application is a division of my application Serial No. 228,729, filed October 26, 1927.

This invention has for its primary object 5 to provide a novel ink receptacle and means for detachably securing the receptacle in a printing machine so that it can be easily and quickly removed whenever required and for any purpose.

10 The invention is particularly adapted for printing machines which are used as a part of an office equipment for printing addresses, letters and the like, and in my original application and in the accompanying drawing 15 I have shown the invention embodied in a machine having a revoluble signature printing form to which ink is automatically supplied from the receptacle. Referring to the drawing,

20 Fig. 1 is a sectional elevation showing the invention and associated parts of a machine in which it may be embodied.

Fig. 2 is an enlarged sectional view through the signature roll and ink receptacle.

25 In the drawing 3 designates generally a main frame and 4 a signature frame which is bolted or otherwise rigidly secured to the main frame. A printing device in the form of a signature roll 5 is revolvably mounted on 30 shaft 6 and is fully disclosed and claimed in my other divisional application Serial No. 359,197, filed April 30, 1929. The printing device or signature roll carries a detachable printing form 7 between peripheral flanges 8, 35 which ride on a pair of spaced ink distributing rolls 9 so that the printing form will contact with said rolls to receive ink therefrom. The rolls 9 have shafts 10 which engage alined slots 11 in the upper end of the 40 ink receptacle 12 and when the receptacle is removed from the machine these rolls can be lifted out of the slots for repair or replacement. The rolls 9 have tapered ends which cooperate with the flanges 8 to maintain the 45 rolls in alignment with the printing form 7. An ink supply roll 13 is mounted in the walls of the ink receptacle between and in contact with the distributing rolls to supply ink thereto. The supply roll is spaced from the 50 signature roll so that it will not contact there- with and the arrangement is such that the signature roll will revolve both of the distributing rolls in the same direction and they will revolve the supply roll in the same direction as the signature roll whereby a supply 55 of ink is evenly and smoothly transferred from the supply roll to the distributing rolls and from the distributing rolls to the signature form. The ink receptacle 12 is provided in its bottom with a groove 14 to engage a support which is in the form of a U-shaped rod 15 having out-turned ends 16 engaging the signature frame. A spring 17 is attached at one end to a handle 18 on the support 15 and at its other end to the signature frame to hold the support in up position. The ink receptacle has openings 19 to receive pins 20 on the signature roll frame for registering and holding the ink receptacle in proper position in the machine. Provision 60 is made in a machine of this kind for the adjustment of the signature roll transversely of the machine to print the signature at the proper position on the letter sheet and the ink receptacle being supported and registered 65 and held on the signature frame will be adjusted with the signature roll to properly register therewith. To insert the receptacle in the machine the handle 18 is operated to swing the support downward on its pivots 70 16, whereupon the receptacle may be placed in position on the support with the groove 14 engaging the support as shown in Fig. 1. Then the handle is released and the support is swung to up position by the spring 17, 75 85 engaging the openings 19 with the pins 20 to register the ink receptacle with the signature roll and engaging the distributing rolls 9, 9 with the flanges 8, 8 of the signature roll so that they will distribute ink onto the face 90 of the type form held between the flanges. The ink receptacle may be removed from the machine by depressing the support and withdrawing the receptacle from the support. The receptacle may be provided with a handle 95 21 to facilitate inserting the receptacle in the machine and removing it therefrom. A lever 22 is pivoted at 23 on the outside of the receptacle 12 and it projects into the receptacle below the ink rolls and carries an ab- 100

sorbent pad 24 which is adapted to absorb ink in the well at the bottom of the receptacle and to engage and apply ink to the supply roll 13. The lever has an extension 25 which is arranged to be engaged by automatic devices comprising the yoke 26 for intermittently swinging the lever to ink the supply roll as described in my original application.

The invention comprises a simple and convenient means for inking the printing form which, in the particular embodiment illustrated and described, is a signature form. Any other printing form may be substituted for the printing form. The supply roll is intermittently supplied with ink from the well of the receptacle through the medium of the movable absorbent pad 24 and the supply roll evenly applies the ink to the distributing rolls which in turn evenly apply the ink to the printing form. The receptacle including the supply and distributing rolls and the applying pad with its lever, constitutes a unit which is bodily inserted in the machine and removed therefrom. Provision is made for easily registering the receptacle with the printing form so that the rolls will properly apply the ink to the form. The invention is shown in part of a printing machine which is fully disclosed in my original application but it is adapted to other machines and changes in the form, construction and arrangement of parts may be made for this or other purposes within the scope of the following claims.

I claim:

1. In a printing machine, the combination of a rotatable printing device including a printing form and having flanges thereon, a bodily movable ink receptacle, means in said ink receptacle engageable with said flanges to receive movement therefrom to apply ink to the form, and means registering said ink receptacle and said inking means in operative relation with the form to engage said inking means with said flanges.
2. In a printing machine, the combination of a printing form, a bodily movable ink receptacle, distributing rolls mounted in the receptacle for applying ink to the form, a supply roll mounted in the receptacle intermediate of said distributing rolls and in contact therewith, means for supplying ink from the well at the bottom of the receptacle to said supply roll, and means for yieldingly supporting the ink receptacle with said rolls yieldingly engageable with the printing form.
3. In a printing machine, the combination of a printing form, a bodily movable ink receptacle, means in the ink receptacle for applying ink to the form and comprising spaced distributing rolls to engage the form, a supply roll disposed between and in contact with the distributing rolls, an absorbent pad, and

a lever pivotally mounted on the receptacle and carrying said pad to enter the supply of ink in the well at the bottom of the receptacle and to engage the supply roll.

4. In a printing machine, the combination of a printing form a bodily movable ink receptacle, means in the ink receptacle for applying ink therefrom to the form and comprising a pad, a lever pivotally mounted on the receptacle and carrying said pad, and means for intermittently operating said lever.

5. In a printing machine, the combination of a frame, a rotatable printing device including a printing form and having flanges thereon, a bodily movable ink receptacle, means in the receptacle engageable with said flanges to receive movement therefrom and to be maintained in alignment with the form and adapted to apply ink to the form, means yieldably supporting the ink receptacle with said inking means in operative relation with the form and comprising a support pivoted at one end on the frame, and a spring connected with the frame and the free end of said support to insure engagement of said inking means with said flanges.

6. In a printing machine, the combination of a frame, a printing form, a bodily movable ink receptacle, means in the receptacle for applying ink therefrom to the form, and means for yieldingly supporting the ink receptacle with said inking means in operative relation with the form, said ink receptacle having a groove to engage said support for positioning the receptacle on the support.

7. In a printing machine, the combination of a frame, a printing form, a bodily movable ink receptacle, means in the receptacle for applying ink therefrom to the form, and means for yieldingly supporting the ink receptacle with said inking means in operative relation with the form and comprising a yoke-shaped wire pivoted to the frame, a spring connected to the frame and to the free end of the yoke, and means for positioning the receptacle on the yoke.

8. In a printing machine, the combination of a rotatable printing device including a printing form and having flanges thereon, an ink receptacle, an ink distributing roller in said ink receptacle and engaged with said flanges to be rotatable therewith and to be maintained in alignment with the printing form, and an ink supply roller mounted in said receptacle for supplying ink to said ink distributing roller.

9. In a printing machine, the combination of a rotatable printing device including a printing form and having flanges thereon, an ink receptacle, an ink distributing roller in said ink receptacle and engageable with said flanges to be rotatable therewith, said ink distributing roller having portions thereon cooperating with said flanges to maintain

said roller in alignment with said form, an ink supply roller engaged with said ink distributing roller to supply ink thereto, and means in the ink receptacle for transferring 5 ink from the receptacle to the ink supply roller.

10. In a printing machine, the combination of a printing device having spaced circumferential flanges thereon and a printing 10 form on the periphery thereof intermediate said flanges, an ink receptacle, ink distributing rollers in said ink receptacle and engaged with said flanges to be aligned with the printing form and to be rotatable with the 15 printing device to apply ink to said printing form, and means acting on said ink receptacle for holding said distributing rollers in engagement with said flanges.

11. In a printing machine, the combination 20 of a printing form, an ink receptacle having slots in opposite walls thereof, an ink distributing roller including a shaft passed into slots to rotatably support said ink distributing roller, and means acting on 25 said ink receptacle to hold said ink distributing roller in engagement with said printing form.

12. In a printing machine, the combination 30 of a frame, a printing form, a bodily movable ink receptacle having a groove in the lower wall thereof, means in the ink receptacle for applying ink therefrom to the form, a substantially U-shaped bracket pivotally mounted on said frame and having a portion 35 thereof engaged in the groove in the lower wall of said receptacle, and spring means holding said bracket in said groove and urging said ink receptacle toward said form.
